UNITED STATES PATENT OFFICE.

HEINRICH REINHARDT, OF BIEBRICH, GERMANY, ASSIGNOR TO THE FIRM OF KALLE & COMPANY, AKTIENGESELLSCHAFT, OF BIEBRICH, GERMANY.

MANUFACTURE OF DIACIDYL AND HIGHER ACIDYLATED COMPOUNDS FROM AMINO-AZO BASES.

1,076,840.

Specification of Letters Patent.

Patented Oct. 28, 1913.

No Drawing.

Application filed September 9, 1912. Serial No. 719,421.

To all whom it may concern:

Be it known that I, HEINRICH REINHARDT, doctor of philosophy and chemist, a subject of the Grand Duke of Hesse, residing at 5 Biebrich-on-the-Rhine, Germany, have invented certain new and useful Improvements in the Manufacture of Diacydyl and Higher Acidylated Compounds from Amino-Azo Bases, of which the following is a specifica- 10 tion.

In the "Berichte der Deutschen Chemischen Gesellschaft" vol. 17, pages 463 and 470, are described the acetyl-amido-azo-benzene (melting point 141° centigrade) and 15 acetyl-amido-azo-toluene (melting point 185° centigrade), both being obtained by heating the corresponding bases with acetic anhydrid. The amino-azo-benzene derivative has been obtained by Berju, see 20 Berichte, vol. 17, page 1400, (melting point 143° centigrade), and indirectly also by Pawlewski, see Berichte, vol. 35, page 113 (melting point from 144° to 146° centigrade). Of the amino-azo-toluene derivative brief mention is made in the specifica- 25 tion of German Patent No. 88,013. In all these cases only the mono-acetyl derivatives were obtained.

I have found, that amino-azo-benzene, its 30 derivatives, homologues and analogues, contrarily to many other amines, are capable of very ready conversion into very stable diacydyl and especially di-acetyl compounds of the following general formula

where R and R' are the aromatic nuclei of the acyldiamido-azo compounds. If the amino-azo derivatives used possess several 40 amino groups, even a higher acylation is possible. In order to obtain this result it is necessary to work with sufficiently large excess of the acylating agent and to employ a high temperature for a sufficiently 45 long period. The employment of the acetylating agents usually employed in lieu of acetic anhydrid presents no advantage in practice. For instance, as also stated by Berju, boiling with glacial acetic acid gives

50 only mono-acetyl-amido-azo-benzene and likewise mono-acetyl-azo-toluene can be obtained in the same manner and moreover the yield is not good and dark colored by-products are formed. The conditions are

similar when for instance acetyl chlorid is 55 employed.

The following are examples of how this invention may be carried out in practice, but the invention is not limited thereto.

Example I: 50 kilograms of amino-azo- 60 toluene are boiled in a reflux condenser with about 150 kilograms of acetic anhydrid with the addition of from 10 to 20 kilograms of sodium acetate until (usually after from 4 to 10 hours) a sample of the melt on cooling 65 no longer deposits crystals. The melt is then precipitated with water either directly, or after removal of the excess of anhydrid and acetic acid, and the raw product which soon solidifies is recrystallized out of alcohol for 70 instance. In this way nearly a practically theoretical yield of the di-acetyl compound of the amino-azo-toluene of the following formula:

75

is obtained. Separation from the small 80 amounts of mono-acetyl derivative which are sometimes present is scarcely necessary. Di-acetyl-amido-azo-toluene forms long red-dish-yellow needles having a melting point of 65° centigrade, or thick crystals of a fine 85 red color similar to potassium dichromate, which crystals have a melting point of 75° centigrade. In both crystalline forms it readily dissolves in many solvents, while the mono-acetyl derivative is difficultly soluble, or even only soluble in traces. It is therefore possible to remove even small amounts of the mono-acetyl compound. The statement of Schultz (Berichte 17, page 470) that acetyl-amido-azo-toluene (melting point 95 185° centigrade) is readily soluble in alcohol is erroneous.

Example II: 50 kilograms of amino-azo-benzene are boiled in a reflux condenser with from about 200 to 250 kilograms of acetic 100 anhydrid, preferably with the addition of 20 kilograms of sodium acetate, until a sample of the melt on cooling no longer precipitates crystals. In other respects the process is the same as in Example I. The di-acetylation of the amino-azo-benzene takes place somewhat more difficultly than does the di-acetylation of the corresponding toluene 105

compos. 1, and consequently in the use of so small an amount of acetic anhydrid as mentioned in Example I, too much mono-acetyl derivative is produced. Di-acetyl-amido-
5 azo-benzene

10

forms long thin lamellæ having a melting point of from 103° to 104° centigrade and is but feebly colored. Its general power of solubility is about the same as that of the toluene derivative. The differences in the dissolving power compared with the mono-acetyl derivative are not however so favorable and therefore repeated recrystallization (for instance out of chloroform-ligroin) 15 is necessary to effect a complete separation.

In lieu of the compounds mentioned in the foregoing examples, other amido-azo compounds of the benzene, or naphthalene series can be used, f. i. the substitution products or homologues thereof.

The new compounds are suitable for use in therapeutics. Compared with the amino-azo compounds themselves, they are distinguished by the fact that they are not poisonous and not irritant. They have over the difficultly soluble mono-acidyl derivatives the advantage of greater solubility, while they are more economical in use and have a more intense action.

25 I claim:

1. The process of producing from amino-azo bases acidyl compounds containing at least one acidyl group more than the number of amino groups, which process consists 30 in heating the said bases with an excess of an acylating agent over the amount theoretically required.

2. The process of producing from amino-azo bases acetyl compounds containing at 35 least one acetyl group more than the number of amino groups, which process consists in heating the said bases with an excess of an acetylating agent over the amount theoretically required.

50 3. The process of producing from amino-azo bases acetyl compounds containing at least one acetyl group more than the number of amino groups, which process consists in heating the said bases with an excess of 55 acetic anhydrid over the amount theoretically required.

4. As new products the acidyl compounds

from amino-azo bases containing at least one acidyl group more than the number of amino groups and obtainable by heating 60 amino-azo bases with an excess of an acidylating agent over the amount theoretically required.

5. As new products the acetyl compounds from amino-azo bases containing at least 65 one acetyl group more than the number of the amino groups and obtainable by heating 70 amino-azo bases with an excess of an acetylating agent over the amount theoretically required.

6. As new products diacidyl derivatives of mono-amino-azo bases, obtainable by heating 75 amino-azo bases with an excess of an acidylating agent over the amount theoretically required, insoluble in water and generally 80 soluble in organic solvents.

7. As new products diacetyl derivatives of mono-amino-azo bases, obtainable by heating 85 amino-azo bases with an excess of an acetylating agent over the amount theoretically required, insoluble in water and generally 90 soluble in organic solvents.

8. As new products diacidyl-amino derivatives of amino-azo bases of the benzene series of the following general formula

where R and R' are aryl nuclei, insoluble in water, generally soluble in organic solvents, and crystallizable therefrom.

9. As new products diacetyl-amino derivatives of amino-azo bases of the benzene series of the following general formula

where R and R' are aryl nuclei, insoluble in water, generally soluble in organic solvents, and crystallizable therefrom.

10. As a new product the diacetyl-amino-azo-toluene, insoluble in water readily soluble in the usual organic solvents, and crystallizing therefrom either in long reddish-yellow needles of a melting point of 65° centigrade or in thick crystals of a bright 100 red color melting at 75° centigrade.

In testimony whereof I have signed my name to this specification in the presence of two subscribing witnesses.

HEINRICH REINHARDT
